CLAIM

(57) The ornamental design for a filter element having a pattern, as shown and described.

DESCRIPTION

FIG. 1 is a perspective view showing the new design for a filter element having a pattern;

FIG. 2 is an enlarged portion of FIG. 1, which is representative of the remainder of the pattern illustrated in FIG. 1; FIG. 3 is a front view of FIG. 1;

FIG. 4 is an enlarged portion of FIG. 3, which is representative of the remainder of the pattern illustrated in FIG. 3; FIG. 5 is a rear view of FIG. 1;

FIG. 6 is a right side view thereof;

FIG. 7 is a left side view thereof; and,

FIG. 8 is a top view thereof, the bottom being a mirror image thereof.

The evenly spaced broken lines shown in the drawings depict portions of the filter element having a pattern and form no part of the claimed design. The dot-dot-dash broken lines represent boundaries of the claimed design.
